COMPOSITE SHIPPING CASE

Filed July 6, 1926

UNITED STATES PATENT OFFICE

PAUL F. BOEYE, OF ST. PAUL, MINNESOTA, ASSIGNOR TO WALDORF PAPER PRODUCTS COMPANY, A CORPORATION OF MINNESOTA

COMPOSITE SHIPPING CASE

Application filed July 6, 1926. Serial No. 120,692.

This invention relates to shipping cases, certain of the exterior walls of which, are constructed of corrugated board and others of solid fiber board.

5 It is my object to minimize the cost and weight of shipping cases, and at the same time to retain ample strength by constructing the normally weaker walls from solid fiber board, and the other exterior walls 10 from corrugated board, the seams joining the walls being formed entirely from solid portions of the board.

More particularly, it is my object to form on the corrugated walls of such cases integral flanges or margins of solid and relatively tough board, adapted to be secured by wire stitching to other solid fiber portions of the cases.

Heretofore, shipping cases have been 20 formed with certain of the exterior walls constructed of solid fiber board and certain others of corrugated board, but it has been considered necessary either to secure the several walls together by adhesive or to insert wire 25 stitches through the corrugated board into the fiber board and to clinch the stitches on the side of each seam which is formed from solid fiber board. However, as corrugated board is frequently constructed from sheets 30 which are equally as tough and durable as the sheets from which solid fiber board is constructed, it will be evident that the apparent weakness of the corrugated board is due to its compressible nature, caused by the 35 hollow spaces between corrugations in the core. Thus, corrugated board is unsuited to receive wire stitches in a seam of a box, because the stitches tend to tear through the. several layers of such board successively at 40 the point where the stitches cross the surface of the board. I have discovered that the difficulty of stitching corrugated portions of a box to other portions may be overcome by treatment of the margins of flanges 45 incorporated in the seams in such a manner that the board is reduced to solid fiber at the points of attachment. In my improved box, the wire stitches may be driven through and clinched upon a surface of 50 either the fiber board panel or upon the solid

margins of the corrugated board, and the application of the invention is not limited to boxes in which solid fiber walls are accessible for engagement with the clinching head of a stitching machine.

With these objects in view, my invention will be best understood by reference to the accompanying drawings, in which Figure 1 is a perspective view of my improved box with the cover closed and one of the corners cut off to show the construction of one of the end seams; Fig. 2 is a section taken on the line 2—2 of Fig. 1 with the cover of the box partially open; Fig. 3 is a fragmentary section taken on the line 3—3 of Fig. 1 with the cover open; Fig. 4 is a fragmentary plan view of the component blanks of sheet material laid flat and Fig. 5 is an enlarged fragmentary section through a corner of the box showing the solid fibre flange on the corrugated blank overlapping an end blank.

My improved shipping case is formed from a main body blank, which is creased along lines 5, parallel to the corrugations, to form longitudinal corners of the box. The 75 creases thus divide the main corrugated blank into a bottom 6, two longitudinal sides 7 and two cover flaps 8. At each end of the several walls 6, 7 and 8, a series of flanges 9, 10 and 11 are formed by creasing transverse 80 the creases 5 and by cutting slots of the required depth between the several flanges. Two similar ends 12 of the box are formed from solid fiber blanks, each having an integral cover panel 13 and a base flange 14 85 produced by crease lines 15.

The end flanges 9, 10 and 11 of the corrugated sheets are rendered tough and solid by treatment during the manufacture of the board. This treatment consists in rolling 90 flat bands of the desired width in the corrugated core before said core is attached to the surface sheets of the board, and in applying adhesive to the inner sides of the surface sheets, and then pressing the portions 95 of the surface sheets with adhesive thereon upon the flattened core, pressure being applied to the solid portions of board thus produced until the adhesive has set and a tough, solid fiber portion is produced. Subse- 100

quently, the sheet having solid fiber portions is so cut that the solid fiber portions are along the margins forming the flanges 9, 10 and 11.

In the manufacture of the boxes, the base flanges 14 on the solid fiber ends 12 are fastened by wire stitches 17 upon the outer surface of the bottom panel 6 at each end. Thus, the blank cases are shipped flat to be finally assembled by the packer of the goods before the cases are filled. To extend the blanks in box form, the ends 12 are folded to their position perpendicular to the bottom 6, and the flanges 10 are then folded into engagement with the outer surfaces of the ends 12. Now the flanges 10 are secured by wire stitches 16 driven through said flanges into the margins of the ends 12, and the flanges 9, which extend on the inner surfaces of the ends 12, are secured in place by driving wire stitches 18 from the outside of the box through the end panel 12 and clinching said stitches upon the inner surfaces of the flanges 9. The boxes, thus completed, are ready to be filled, and after the goods to be shipped have been placed therein, the cover flaps 8 are first folded in upon the top of the goods with the flanges 11 extending downward, adjacent to the inner surfaces of the ends 12. Finally, the cover flaps 13 are folded upon the outer surfaces of the flaps 8 and are, preferably, secured in place by adhesive.

It will be noted that in the construction of my improved case the wire stitches 17 merely hold the base flanges 14 in place and are not depended upon to give strength to the joints between the corrugated bottom and solid fiber ends. The stitches 18 engaging the solid fiber flaps 9 give the box ample strength at the base corners of the end. It will further be noted that in assembling the shipping case of this invention, the wire stitches may be driven so as to be clinched either upon the surfaces of the solid flanges 9, 10 and 11, as in case of the stitches 18, or as in the case of the stitching 16, on the inner surfaces of the ends 12.

Having described my invention what I claim as new and desire to protect by Letters Patent is:

1. In a composite shipping case, formed from a plurality of blanks, at least one of said blanks being constructed from corrugated board having liner and corrugated members secured together, and another blank being formed from solid fiber board, marginal portions on said corrugated blank formed from relatively solid and tough board in which said members of the corrugated board are compressed and retained in compressed relation by adhesive and a seam joining said solid fiber and corrugated blanks together and comprising overlapped portions of the solid fiber blank and solid

marginal portions of said corrugated blank, secured together by wire stitches.

2. In a composite shipping case, having a plurality of walls constructed from separate blanks, at least one of said walls being constructed from corrugated board having liner and corrugated members secured together and another wall of the case being formed from solid fiber board, a relatively tough and solid flange formed integral with said corrugated wall and adapted to be folded into engagement with said solid fiber wall, said members of the corrugated board in said flange being compressed and retained in a compressed relation by adhesive and a seam formed by stitching said flange to said solid fiber wall.

3. In a composite shipping case having certain of its exterior walls constructed from corrugated board having liner and corrugated members and certain other of the exterior walls constructed of solid fiber board, integral flanges of solid fiber board formed on the corrugated walls to overlap portions of the solid fiber walls, the members of said corrugated board in said flanges being compressed and retained in compressed relation by adhesive and seams for joining a corrugated board wall to the solid fiber board walls, formed with wire stitches extending through said solid fiber flanges and solid fiber walls of the case, said stitches being clinched upon a surface of said flanges.

In testimony whereof, I have hereunto signed my name to this specification.

PAUL F. BOEYE.
